Primary Examiner—Cathy Anne MacCormac

(57) **CLAIM**

I claim the ornamental design for a helical pet toy, as shown.

DESCRIPTION

FIG. 1 is a front perspective view of a helical pet toy showing my design;

FIG. 2 is a side elevation view thereof; the top, bottom, and opposite side all being identical;

FIG. 3 is a rear view thereof, the front view being a mirror image;

FIG. 4 is a front perspective view of a second embodiment of FIG. 1;

FIG. 5 is a side elevation view thereof; the top, bottom, and opposite side all being identical;

FIG. 6 is a front view thereof, the rear view being a mirror image.

FIG. 7 is a front perspective view of the third embodiment showing my design;

FIG. 8 is a side elevation view thereof; the top, bottom, and opposite side all being identical; and,

FIG. 9 is a front end view thereof; the rear end being a mirror image.
